(57) **CLAIM**

The ornamental design for a packaging, as shown and described.

DESCRIPTION

1. Packaging

1.1 is a perspective view of a packaging comprising a new ornamental design;
1.2 is a front view thereof;
1.3 is a left view thereof;
1.4 is a top view thereof;
1.5 is a right view thereof;
1.6 is a back view thereof; and
1.7 is a bottom view thereof.

The parts shown by means of broken lines in the reproductions are not part of the claimed design.
